[57] CLAIM

The ornamental design for a combined knife set and rack, substantially as shown and described.

DESCRIPTION

FIG. 1 is a front elevational view of a combined knife set and rack showing our new design;

FIG. 2 is a top plan view thereof;

FIG. 3 is a side elevational view thereof;

FIG. 4 is a rear elevational view thereof;

FIG. 5 is a front perspective view of the rack thereof, the knife set having been omitted for convenience of illustration;

FIG. 6 is a front elevation of the left and first knife of the combined knife set and rack;

FIG. 7 is a top view of the FIG. 6 knife;

FIG. 8 is a bottom view of the FIG. 6 knife;

FIG. 9 is a handle end view of the FIG. 6 knife;

FIG. 10 is a blade end view of the FIG. 6 knife;

FIG. 11 is a front elevation of the second knife thereof;

FIG. 12 is a front elevation of the third knife thereof;

FIG. 13 is a front elevation of the fourth knife thereof;

FIG. 14 is a front elevation of the fifth knife thereof;

FIG. 15 is a front elevation of the sixth knife thereof; and

FIG. 16 is a front elevation of the seventh knifethereof. The handles of the knives shown in FIGS. 11-16 are similar to the handle shown in FIGS. 7-10.
